(57) **CLAIM**

The ornamental design for a component of a block game, as shown and described.

DESCRIPTION

FIG. 1 is a perspective view of a component of a block game showing our new design;

FIG. 2 is a front-side elevational view thereof;

FIG. 3 is a back-side elevational view thereof;

FIG. 4 is a left-side elevational view, the right-side elevational view being a mirror image thereof;

FIG. 5 is a perspective view of a block game environment including the component of the block game shown in FIG. 1; and,

FIG. 6 is an exploded perspective view thereof.

Broken lines in the figures illustrate environmental structure and/or portions of the component of the block game that form no part of the claimed design.
